UNITED STATES PATENT OFFICE.

WILLIAM C. COLEMAN, OF WICHITA, KANSAS.

SEPARATOR.

Application filed October 8, 1923. Serial No. 667,203.

To all whom it may concern:

Be it known that I, WILLIAM C. COLEMAN, a citizen of the United States, residing at Wichita, in the county of Sedgwick and State of Kansas, have invented certain new and useful Improvements in Separators; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to centrifugal separators whereby particles of precious metal may be separated from ore pulp by centrifugal force and the use of mercury, which as is well known has an affinity for gold and silver. The invention contemplates a rotor and a stator with a return baffle co-operating therewith so that after the pulp has passed through the rotor the heavier particles may be returned to be worked over and provision is made whereby the pulp will have a relatively slow movement through the separator, although a relatively large quantity of material will be subjected to the action of centrifugal force and the mercury at all times.

The invention contemplates the provision of certain novel inexpensive, easily constructed parts, all of which will be referred to hereinafter, reference being had to the accompanying drawings, in which

Fig. 1 is a vertical longitudinal sectional view through a separator constructed in accordance with my invention.

Fig. 2 is a perspective view of the return baffle, and

Fig. 3 is a fragmentary edge view of the baffle.

Referring now to the drawings by numerals of reference:

1 designates a shaft which may be driven by any suitable means and which may be appropriately supported in bearings if desired. The shaft 1 is fastened into a cover plate 2 for the rotor 3 which is carried by the cover plate and secured thereto through the medium of the bolts 4.

The rotor comprises a circumferential wall having a concave inturned bottom 5 at the center of which is an opening 6 surrounded by a collar 7 in which is supported an upstanding over flow tube 8. The collar

is provided at its upper end with an outwardly projecting flange or circumferential baffle 9. The wall 3 is recessed to receive a column of mercury 10 which is the material for separating out the precious metal from the ore pulp. The cover plate 2 is provided with depending radial impeller blades or wings 11 mounted about the axis of the shaft 1 and adapted to distribute the ore pulp over the disk or table 12 supported on the hollow shaft or tube 13 through which the material is introduced into the machine. The pulp may be forced through the tube 13 in any appropriate manner, discharging upon the table or disk 12 and after the rotor turns about its axis the impeller blades 11 will throw the material over the peripheral lip 14 on the edge of the disk 12 and since the diameter of the disk is less than the diameter of the cover the material can pass into the separating chamber 15 formed by the body of mercury and in a partition valve or return baffle 16 consisting of the members 17 and 18 bolted to the flange 19 on the bottom of the disk 12 and to the upstanding flange 20 on the Z-shaped baffle 21 supported by the members 17 and 18.

It will be observed that the members 17 and 18 are slightly eccentric to the rotor and that they consist of two semi-cylindrical plates having overlapping edges, that is the edge 22 of the plate 17 overlaps the underlapping edge 23 of the plate 18 and the edge 24 of the plate 18 overlaps the underlapping edge 25 of the plate 17 so that spaces 26 and 27 are provided between the edges of the respective plates 17 and 18, the spaces existing only near the ends of the cylinder formed by the plates 17 and 18, the intermediate portions being closed by the filler bars 28 and 29 and it will be noted that part of the collar 7, the flange 9 and the tube 8 are inside the partition formed by the members 17 and 18 and that the flange 9 is spaced from the bottom flange 30 of the Z-shaped baffle 21 and further that the outstanding flange 31 of the Z-shaped baffle 21 extends nearly to the wall of the rotor, consequently a tortuous passageway is provided between the outlet of the rotor and the inlet of the stator consisting of the disk 12, the members 17 and 18 and the Z-shaped baffle 21.

It will be further observed that the chamber 15 is of considerable capacity so that a relatively large amount of pulp will be in

the machine at all times while the machine is functioning and since the pulp will be at all times more or less agitated, due to the fact that there will be a certain amount of 5 scour on the mercury to set the material in motion and in view of the fact that the material is passing longitudinally through the machine the pulp will be pretty thoroughly treated before it leaves the rotor, but as it 10 passes up through the closed passageway into the stator on its way to the outlet tube 8 the heavier particles will flow to the outer edge of the stator and pass out through the spaces between the edges 22, 23, 24 and 15 25 of the members 17 and 18, back through the chamber 15 to again be treated, the members 17 and 18 acting as return baffles so that part of the pulp that has entered the stator can be returned to the rotor to be 20 worked over. The lighter material will pass out through pipe 8.

By making the chamber 15 relatively large and properly proportioning the amount of material entering the machine 25 the passage of the pulp through the machine will be relatively slow so I have termed the chamber 15 a retarding chamber, the purpose being to maintain the speed of the material retarded as much as practicable as it 30 passes through the machine and it will be apparent that the retarding action will be assisted by the Z-shaped baffle or flange 9 and it will further be apparent that the heavier particles of material entering the 35 stator will accumulate along the inner face of the eccentric plates 17 and 18 and pass back into the chamber 15 so that the separator will be highly efficient and a large recovery of metal from the ore pulp will result.

What I claim and desire to secure by Letters Patent is:

1. A separator including two hollow members, one of which is a rotor and the other a stator, one within the other in spaced relation, a body of mercury in the rotor, means 45 for introducing material to one of the members, means for discharging material from one member to the other member and means for returning some of the material to the first member.

2. A separator comprising two hollow members, one of which has rotatable movement with respect to the other, one of the 55 members being within the other, a body of mercury in one of the members, means for introducing ore pulp into one of the members, means for discharging the ore pulp into the other member and means for returning some of the pulp to the first member, the first member having a discharge opening.

3. A separator comprising a hollow rotor member and a hollow stator member, one 60 within the other in spaced relation, a body 65

of mercury in the rotor member, means for introducing material into the rotor member, means for discharging the material from the rotor member to the stator member, the stator member having an exhaust and means 70 for returning some of the material from the stator member to the rotor member.

4. A separator comprising a hollow rotor, impeller blades within the rotor, a collar on the bottom of the rotor surrounding 75 a discharge opening, a feed tube projecting through the discharge opening, the feed tube being of lesser diameter than the collar, a disk at the discharge end of the feed tube and adjacent to the impeller blades, a circular wall depending from the disk consisting of two eccentrically disposed curved plates having overlapping edges with spaces between them and baffles in the lower portion of the rotor to provide a tortuous passage 80 communicating the rotor with the space within the partition formed by the two eccentric plates.

5. A separator comprising a hollow rotor having inwardly and upwardly curved bottom, a collar in the bottom surrounding a discharge opening, depending impeller blades carried by the top of the rotor, a distributor disk immediately below the 90 blades, a hollow feed tube connected to the disk and adapted to discharge material on to the disk through the opening therein, a pair of curved plates depending from the disk having overlapping edges with spaces 95 between them to form a substantially circular partition spaced from the wall on the rotor and a circular baffle member at the edges of the plate.

6. A separator comprising a hollow rotor having an inwardly and upwardly curved bottom, a collar in the bottom surrounding a discharge opening, depending impeller blades carried by the top of the rotor, a distributor disk immediately below the blades, a hollow feed tube connected to the disk and adapted to discharge material on to the disk through the opening therein, a pair of curved plates depending from the disk having overlapping edges with spaces between them to form a substantially circular partition spaced from the wall on the rotor and a circular baffle member at the edges of the plate, substantially Z-shaped in cross section.

7. A separator comprising a hollow rotor having an inwardly and upwardly curved bottom a collar in the bottom surrounding a discharge opening, depending impeller blades carried by the top of the rotor, a distributor disk immediately below the 110 blades, a hollow feed tube connected to the disk and adapted to discharge material on to the disk through the opening therein, a pair of curved plates depending from the disk having overlapping edges with spaces 115 between them to form a substantially circular partition spaced from the wall on the rotor and a circular baffle member at the edges of the plate, substantially Z-shaped in cross section.

between them to form a substantially circular partition spaced from the wall on the rotor and a circular baffle member at the edges of the plate, substantially Z-shaped in 5 cross section, comprising a web having an inwardly disposed flange and an outwardly disposed flange, the outwardly disposed flange being of greater width than the inwardly disposed flange.

10 8. A separator comprising two hollow members, one within the other, one member

being stationary and the other one being rotatable, a body of mercury in the rotatable member, means for introducing material in one of the members, means for causing material to pass from the first member into the second member and means for discharging material from the second member and means for returning some of the material from the second member to the first. 15

20 In testimony whereof I affix my signature.
WILLIAM C. COLEMAN.
